APPARATUS FOR COATING SHEET METAL

Harry Sebell, Newton, Mass., assignor of one-half to Arthur H. Parker, Lexington, Mass.

Application February 26, 1941, Serial No. 380,663

1 Claim. (Cl. 91—12.2)

This invention relates to the art of tinning sheet metal, that is, applying a coating of tin to sheet metal.

One form of apparatus now commonly used for tinning sheet metal comprises a tin pot containing molten tin through which the sheet or strip to be tinned is fed, said tin pot being formed on its entering side, that is, the side at which the sheet or strip enters the molten tin, with a flux box containing flux, and also being formed on its discharge side, that is, the side at which the sheet or strip is discharged, with a compartment containing palm oil or other suitable oil through which the tinned sheet is discharged as it emerges from the bath of molten tin. Such machines are generally provided with a pair of squeeze rolls in the body of oil which have for their purpose to regulate the thickness of the coating of tin with which the sheet metal is provided. These squeeze rolls have to be very accurately made and very carefully set. If the squeeze rollers are set too far apart, then the coating of tin which is left on the sheet may be unnecessarily thick. If the surface of each squeeze roll is not perfectly true and perfectly smooth, the result may be imperfect tinning.

During the use of a tinning apparatus of this type, impurities in particle form, such, for instance, as iron-tin alloy particles, scale, rust, dirt, grit, etc., accumulate in the oil bath, and if any such particles are present on the surface of the tinned sheet when it passes between the squeeze rolls, such particles may become embedded in the tin sheet by the pressure of the squeeze rolls, thereby producing a pin hole, black spot, or undesirable imperfection in the tin coating, or said particle may adhere to the surface of the squeeze roll, thereby producing an imperfect surface thereon.

It is one of the objects of my present invention to provide a novel substitute for the squeeze rolls by which the thickness of the tin coating that remains on the sheet may be controlled, which substitute is free from the disadvantages above referred to and that are apt to result from the use of squeeze rolls. This substitute is in the form of high pressure jets of oil or other suitable fluid which are delivered against the tinned surface as it is passing through the oil bath, such high pressure jets serving not only to wash off from the sheet any impurities in particle form, but also serving to wash off from the sheet any surplus tin thereby leaving on the sheet an even tin coating of the desired thickness.

In order that these high pressure jets of oil or

other fluid may be effective in washing off impurities and surplus tin from the sheet or strip as it emerges from the bath of molten tin, it is important that such jets should impinge on the coated sheet while the tin coating is still in a fluid, freely flowing condition and before the coating hardens to any extent.

Accordingly, another object of my invention is to provide a novel apparatus of this sort in which the tin coating which has been applied to the sheet is kept in a heated fluid condition until after the sheet has passed between the oil jets and has been subjected to the action thereof.

A further object of the invention is to provide an improved construction by which the temperature of the oil which is delivered from the oil jets may be controlled independently of the temperature of the molten tin in the tin pot, so that such oil may be used at a temperature which is either lower or higher than that of the molten tin.

One advantage of this is that the thickness of the coating of tin which remains on the strip can be controlled by varying the temperature of the oil. If the oil is kept at a temperature lower than that of the molten tin, the oil jet will have a cooling effect on the tin, and as a result, less of the tin which adheres to the strip will be washed off by the jets than if the oil were kept at a temperature higher than that of the molten tin. Consequently, increasing the temperature of the oil issuing from the jets will result in a thinner coating of tin adhering to the sheet, while lowering the temperature of the oil will result in a thicker coating of tin adhering to said strip.

Other objects of the invention are to improve tin-plating apparatus in various other particles as will be more fully hereinafter set forth.

In the drawings:

Fig. 1 is a vertical sectional view through a plating apparatus embodying my invention.

Fig. 2 is a side view thereof looking from the side away from the observer in Fig. 1.

Fig. 3 is a top plan view.

Fig. 4 is an enlarged vertical section through the drum 14 in Fig. 1.

Fig. 5 is a fragmentary sectional view showing the means for driving the pressure rollers.

Fig. 6 is a fragmentary sectional view showing the oil jets.

In the drawings, 1 indicates a tin pot of any suitable or usual construction containing a bath 2 of molten tin. This tin pot is shown as mounted in a suitable furnace 3 which may be heated by means of a gas burner 4 or any other suitable way.

The tin pot is formed with the usual partition 5 which extends downwardly to a point somewhat below the level of the molten tin, thereby forming on the entering side of the tin pot a flux box 6 containing flux 7, and also forming on the discharge side of the tin pot a chamber 8 adapted to contain palm oil or other suitable oil 9.

The device is herein illustrated as designed for tinning metal in the form of a strip 10 which is taken from a suitable reel 11 that is shown as being supported in brackets 12 mounted on the furnace 3. This strip of metal extends from the reel 11 over a direction roller 13 which is mounted on the tin pot, and from the roller 13, the strip passes downwardly through the flux bath 7 and into the bath 2 of molten tin. Situated within the bath of molten tin is a relatively large feed roll or drum 14 around which the strip passes, said strip then moving upwardly through the bath 9 of oil and over a direction roller 15 which is rotatably mounted in uprights or supports 16. From the direction roller 15, the sheet passes downwardly under another direction roller 17 and thence horizontally over still another direction roller 18 from which it passes to a drum 19 on which it is wound.

The drum 14 is a hollow drum, and it serves two purposes. It is positively driven and, therefore constitutes a feed drum for feeding the strip through the bath of molten tin. It is also internally heated so that it constitutes a heating drum for applying heat to the strip 10 while it is passing around through the bath of molten tin.

This drum may be driven in any suitable way, and as herein shown, said drum is provided with two hollow hubs 20 and 21 which are journaled in suitable bearings 80 and 81 secured to the side walls of the tin pot 1. The hub 21 is a long hub which extends through the wall of the furnace 3 and has on its outer end a sprocket wheel 22 that is connected by a sprocket chain 23 with a driving sprocket wheel 24. This driving sprocket 24 is mounted on a shaft 25 suitably journaled in the framework of the apparatus, and it is driven from a motor 26 through some appropriate speed-reducing apparatus that is indicated generally at 27. The motor 26, therefore, drives the shaft 25 on which the sprocket 24 is fast, and said sprocket 24 drives the drum through the sprocket chain 23 and sprocket wheel 22 which is fast on the hub 21 of the drum.

Provision is made whereby the motor 26 may also drive the reel 19 on which the plated strip is wound. For this purpose, the shaft 25 has a sprocket wheel 28 thereon which is connected by a sprocket chain 29 with a sprocket wheel 30 on the shaft 31 of the reel 19. I propose to employ a slip clutch 32 of any usual construction between the sprocket 30 and the shaft 31 to compensate for the increasing size of the roll 33 of tinned strip as the tinning operation proceeds. The feed roll 14 is driven at a constant rate and, therefore, the tinned strip is delivered to the reel 19 at a uniform rate of speed. This will necessitate a gradual decrease in the speed of rotation of said reel as the roll 33 increases in size, and the slip clutch 32 provides for this.

In accordance with my present invention, the tinned surface of the strip 10 is subjected to the action of high pressure jets of oil while it is traveling through the oil bath and while the tin coating which has been deposited on the strip is still in a fluid free-flowing condition. These high pressure oil jets serve not only to wash off any impurities which may be deposited on the sheet,

but they also serve to wash off surplus tin and to leave on the strip a tin coating of uniform thickness.

These high pressure jets of oil are delivered against the sheet by means of nozzles 34 and 35, each of which has a narrow discharge slot of a length equal to the width of the strip 10. These nozzles are arranged at an inclination, one on each side of the strip 10, and, as stated above, are situated in the oil bath 9.

Means are provided for delivering sheet-like jets of oil 39 from these nozzles under pressure, each sheet-like jet being delivered downwardly against the strip 10.

The oil which is thus delivered from the nozzles 34, 35, is taken from a storage tank 36, and the oil compartment 8 is provided with an overflow outlet 37 to which is connected an overflow pipe 38 that leads back into the storage tank 36. The required pressure of the jets 39 of oil as they issue from the nozzles 34, 35, is derived from the operation of a pump 40 which is shown as being operated by a suitable motor 41. The inlet to this pump is connected by a pipe 42 to the bottom of the storage tank 36, and the discharge of the pump is connected to a pipe 43 which is provided with a horizontal portion 44.

Said horizontal portion 44 has two horizontal transverse pipes 45 and 46 connected thereto, which pipes extend across the oil compartment 8. The nozzle 34 is connected to the pipe 45, and the nozzle 35 is connected to the pipe 46. The end 47 of the pipe 46 is closed, but the pipe 45 has an extension 48 that leads back into the storage tank 36. This pipe extension 48 is provided with a shut-off valve 49 by which the pressure at the nozzles can be controlled.

When the pump 40 is in operation, the oil from the storage tank 36 will be delivered through the pipes 43, 44, and nozzles 34, 35, and if the valve 49 is closed, the pressure or force with which the jets 39 are delivered from the nozzles will be the maximum pressure developed by the pump 40. If a reduction in pressure is desired, for any reason, the valve 49 can be opened more or less, thus by-passing some of the oil back into the storage tank.

The operation of the oil jets 39 serve not only to wash off from the plated strip any impurities which may adhere thereto as it passes through the tin pot, but also to wash off from the strip surplus tin, thereby leaving on the strip an even tin coating of the desired thickness. The thickness of the coating which is left on the strip can be varied by varying the pressure with which the jets 39 are delivered from the nozzles 34, 35.

In order that the nozzles may operate effectively, however, it is important that the coating of tin which is adhering to the strip as the strip passes between the nozzles should be in a sufficiently fluid or liquid state so that surplus tin can be readily washed off from the strip by the action of the jets. If the coating of tin which adheres to the strip has begun to solidify to any extent before it is acted on by the jets, then the jets will imperfectly perform their function and will not leave a coating of uniform thickness. To prevent this from happening and to enable the jets to function as desired, I have provided means for heating the feed roll 14. This heating of the feed roll serves to supply heat to the bath of molten tin interiorly of the tin pot, and because the strip 10 is in direct contact with the heated feed roll, the latter serves to supply heat to the strip. As a result, when any portion of the strip 10

leaves the heated feed roll, such portion of the strip will be at a high temperature, as will also be the coating of tin which adheres to the strip. Such coating of tin, therefore, retains its fluid free-flowing condition until it reaches and is acted upon by the jets 39, which, as stated above, operate not only to wash off impurities from the strip, but also to wash off surplus tin.

Any suitable means for heating the feed drum 14 may be employed. I have herein shown a gas burner 51 which is located within the drum and is connected to a supply pipe 52 that extends through the hollow hub 21.

Means are also provided for heating the oil in the storage tank 36, and while any suitable means for this purpose may be used, I have illustrated a gas jet 90 located in a heating compartment 91 beneath the tank and connected to a gas supply pipe 92. The means for heating the oil in the storage tank 36 which is exemplified by the burner 90, will be such that the oil in said tank may be heated to a temperature higher than that of the molten tin if desired, and by regulating the heating means, the oil in the storage tank may be kept at a temperature either the same as that of the molten tin or lower than that of the molten tin. If the oil in the tank 36 is at a lower temperature than that of the molten tin, then the oil jets 39 will have a cooling effect on the tin coating, and while such jets of oil will wash off impurities in particle form and will also wash off surplus tin, yet the cooler temperature of the oil jets will result in a coating of tin of increased thickness remaining on the strip 10.

On the other hand, if the oil in the storage tank is kept at a temperature higher than that of the molten tin, these high-temperature oil jets will prevent the tin from cooling and will, therefore, wash off a greater quantity of the tin which is adhering to the strip, with the result that a thinner tin coating will remain on the strip.

Therefore, by varying the temperature of the oil in the tank 36, it is possible to exercise a control over the thickness of the tin coating which remains on the strip 10.

When the machine is in operation, there is a continuous circulation of oil from the storage tank 36 to and through the nozzles 34, 35, into the oil compartment 8, and from the latter back to the storage tank through the over-flow outlet 37 and pipe 38.

This circulatory movement of the oil will carry most of the impurities which are washed off from the sheet strip 10 through the overflow into the storage tank 36, thus preventing an accumulation of such impurities in the oil bath 9.

The storage tank 36 is provided with a screen or strainer 50 which serves to strain out these impurities, so that oil which is withdrawn from the bottom of the storage tank and delivered to the nozzles is free from such impurities.

Cooperating with the feed drum 14 are two positively driven feed rolls 53 and 54, each roll being driven from the drum 14. For this pur-

pose, the drum has rigid therewith a gear 55, and each feed roll 53, 54 has rigid therewith a pinion 56 which meshes with and is driven by the gear 55. These feed rolls 53, 54, are mounted so that they can be adjusted toward and from the feed drum 14 to accommodate sheets or strips of different thickness. The feed roll 53 is carried in the lower end of a rocking member 57 which is pivotally mounted at 58, and the upper end of which has connected thereto a link 59 that extends through an opening in an abutment 60. The end of the link 59 is screw-threaded and has an adjusting nut 61 thereon. By adjusting this nut 61, the rocker 57 will be turned slightly about its axis 58, thereby moving the feed roll 53 toward or from the feed drum 14.

The feed roll 54 is similarly adjustably mounted, it being carried in the lower end of a rocker 62 pivoted at 63, and the upper end of the rocker 62 has connected thereto a link 64 which extends through an abutment 65 and has an adjusting nut 66 screw-threaded to its outer end.

67 indicate guide plates between which the strip 10 passes as it travels to the feed roll, and 68 25 indicate similar guide plates through which the strip passes as it leaves the feed roll 14. 69 is a curved guide plate encircling the bottom of the feed roll 14 and serving to guide the free end of a sheet or strip from the feed roll 53 around 30 to the feed roll 54 when said sheet or strip is being introduced into the machine.

70 indicates a pressure gauge attached to the pipe section 44 and by which the pressure of the oil can be observed.

35 If desired, I may employ suitable polishing rollers 71, shown in dotted lines in Fig. 1, which are situated to act on the plated strip as it passes from the direction roll 17 to the direction roll 18 and serving to polish the plated surface.

40 I claim:

An apparatus for coating sheet metal comprising a pot containing a bath of molten coating metal, said pot having an oil-containing compartment at the delivery end thereof, means to feed a strip of sheet metal through said pot and through the oil compartment, means to deliver a sheet-like high pressure jet of hot oil against the coated surface of the sheet metal while it is travelling through said oil compartment, thereby 45 to wash surplus coating metal from the sheet metal, means to supply heat to the oil in addition to that which it receives from the molten coating metal, and means to supply heat to the sheet metal in addition to that which it receives 50 from the molten coating metal, the additional heat thus supplied to both the oil and the sheet metal serving to maintain the coating metal which adheres to the sheet metal at a temperature at which it is in a sufficiently free-flowing condition 55 so that the oil jet will wash all surplus coating metal from the sheet metal and leave thereon a thin coating of uniform thickness.

HARRY SEBELL.
